UNITED STATES PATENT OFFICE.

D. HALDEMAN, OF MORGANTOWN, VIRGINIA.

IMPROVEMENT IN MACHINES FOR SOWING SEED BROADCAST.

Specification forming part of Letters Patent No. 17,429, dated June 2, 1857.

To all whom it may concern:

Be it known that I, DAVID HALDEMAN, of Morgantown, in the county of Monongalia and State of Virginia, have invented a new and useful Improvement in Seed-Sowers; and I do hereby declare that the following is a full, clear, and exact description of the construction and operation of the same, reference being had to the annexed drawings, forming part of this specification, in which—

Figure 1 is a top view of the seeder. Fig. 2 is a transverse section on $x x$. Fig. 3 is a transverse section on $y y$. Fig. 4 is a longitudinal section on $z z$, taken through line $m m$ of Fig. 2. Fig. 5 is a transverse section of discharge-regulator and reciprocating scatterer, showing position of stirring-pin projecting upward from the scatterer.

Similar characters of reference denote the same part.

The object of my invention is the graduating of the seed-discharge, effecting the agitation of the seed, and scattering the same after passing from the hopper.

The invention consists of a deep graduating-piece capable of vertical adjustment in a slot through the bottom of the hopper, this piece having alternate recesses cut from the upper edge of one side to the under edge of the opposite, so as to give larger openings as the piece descends through the slot, and having attached to its bottom so as to reciprocate in contact with the same an inclined scatterer, with pins passing upward through the recesses of the said piece, the construction and operation of the aforesaid combination being as follows:

In the drawings, H is the hopper, having a slot passing longitudinally through its bottom in which is the deep graduating-piece G , held in any desired position by the pins a on the ends of the hopper, and the holes b in the slide-pieces c , secured to the ends of the aforesaid graduating-piece G . This piece has the inclined recesses d arranged alternately, as shown in Fig. 1.

To the bottom of the graduating-piece G is attached the scatterer S by screws e , passing through slots f of the scatterer, so as to admit of the reciprocation of the scatterer a distance equal to the length of the slots. This reciprocation is effected by a lever, L , attached to the scatterer by a screw, g , and provided with a slot, which receives the pin h , connected with the hopper. From the scatterer arise pins i , running in the recesses d of the piece G .

In operation the position of the graduating-piece G will determine the size of opening for the seed, and thus regulate the discharge. The reciprocation of the scatterer by the hand of the operator applied to lever L moves the pins i within the recesses d and prevents the packing of the seed. After the passage of the seed from the hopper it falls upon the inclined moving surfaces $n n$, and is thus insured a suitable distribution over the surface of the ground. The raising of the piece G until the scatterer comes in contact with the bottom of the hopper effectually closes the discharge-openings and prevents further discharge.

I am aware that vibrating scatterers with upward-projecting pins have been used in connection with the bottom of the hopper, but incapable of vertical movement. I am also aware of the use of notched bars for graduating the seed-discharge. Therefore I do not wish to be understood as laying claim to these devices of themselves; but

What I do claim is—

The vertically-adjustable graduating-bar G with recesses, as described, in combination with the vibrating scatterer and agitator connected therewith, when said parts operate together as set forth.

In testimony whereof I have hereunto signed my name before two subscribing witnesses.

D. HALDEMAN.
